UNITED STATES PATENT OFFICE.

JACOB POLE, OF HAMDEN, NEW YORK.

TOY DECORATION-WHEEL.

Specification of Letters Patent.

Patented Apr. 6, 1915.

1,134,417.

Application filed November 11, 1914. Serial No. 871,566.

To all whom it may concern:

Be it known that I, JACOB POLE, a subject of the Czar of Russia, residing at Hamden, in the county of Delaware and State of New York, have invented a new and useful Toy Decoration-Wheel, of which the following is a specification.

The invention relates to improvements in toy wind mills or wind wheels.

10 The object of the present invention is to improve the construction of toy wind mills and to provide a simple, inexpensive, and amusing toy equipped with a plurality of reversely rotating wind wheels and provided with means for enabling it to be readily applied to various moving vehicles, such as automobiles, wagons, baby carriages, bicycles, etc.

With these and other objects in view the 20 invention consists in the construction and novel combination of parts hereinafter fully described, illustrated in the accompanying drawing, and pointed out in the claims appended hereto, it being understood that various changes in the form, proportion, size and minor details of construction, within the scope of the claims, may be resorted to without departing from the spirit or sacrificing any of the advantages of the invention.

25 In the drawings:—Figure 1 is a front elevation of a toy wind mill constructed in accordance with this invention and shown applied to a portion of an automobile. Fig. 2 is a longitudinal sectional view of the same, parts being in elevation. Fig. 3 is an enlarged longitudinal sectional view illustrating the manner of mounting the wind mills. Fig. 4 is a perspective view of the outer portion of the toy, the blades or wings being removed. Fig. 5 is a detail perspective view of the clamp.

30 Like numerals of reference designate corresponding parts in all the figures of the drawings.

In the accompanying drawings, in which is illustrated the preferred embodiment of the invention, 1 and 2 designate inner and outer hubs of reversely rotating wind wheels 3 and 4; which are mounted on a longitudinal spindle 5 embedded in a bar or handle 6 and projecting from the outer end 7 thereof. The outer end 7 is tapered to form 35 a cone, which fits in an inner tapered or conical bearing portion 8 of a central open-

ing 9 in the inner hub 1. The outer end 10 of the opening 9 is also tapered or conical to receive the inner end of an oppositely tapered double conical sleeve 11 mounted on 60 the spindle 5 and interposed between the inner and outer hubs 1 and 2. The outer hub is provided with a central opening 12 having inner and outer tapered portions 13 and 14 receiving the outer tapered portion 65 of the sleeve 11 and an outer tapered sleeve or cone 15, which is suitably secured upon the outer end of the spindle 5. By this construction the wind wheels are secured on the projecting portion of the spindle and maintained in spaced relation, and also enabled to rotate freely. The inner and outer hubs, which are preferably rectangular in cross section, and which have flat rectangular side faces, are provided with reversely arranged 70 diagonally disposed grooves 17 and 18, in which are secured the inner ends of blades or wings 19 and 20 set at an angle in a manner similar to the blades of a propeller and adapted, when moved more or less rapidly through the air, to cause the wheels to rotate in opposite directions. The inner wheel preferably rotates to the right and the outer wheel, which is of less diameter than the inner wheel, rotates to the left, but the blades may be arranged in any other suitable manner and may be of any desired size and form and any number of wind wheels may, of course, be employed.

75 The toy is equipped with a clamp composed of fixed and movable sections 21 and 22, provided with bifurcated ends 23 and 24, which embrace the inner portion of the bar or handle 6. The bar or handle 6 is preferably rectangular in cross section, and the sides of the bifurcated end of the section 21 are suitably secured to the bar or handle 6. The bifurcated end of the other section 22 slidably embraces the bar or handle 6 and permits the section 22 to move toward and from the fixed section 21, the bifurcated end 24 forming an interlocking connection and adapted to prevent movement of the section 22 laterally of the bar 95 or handle 6. The sections, which are provided with registering grooves 25 to form an opening for the reception of a handle bar of a bicycle or other part of a vehicle or machine, are connected by a bolt 26 having a thumb screw 27 and adapted to clamp the sections in engagement with the handle

bar or other part to which the toy is applied.

In order to enable the toy to be mounted on an automobile at the front thereof, the sections are equipped with jaws 28 constructed of wire and adapted to engage the radiator cap 29 of an automobile 30, as clearly illustrated in Fig. 2 of the drawing. The jaws 28 are each constructed of a single piece of wire and consist of a transversely curved loop having parallel terminal shanks 31 fitted against and secured to each of the sections of the clamp by one or more bands or wrappings of wire 32 or other suitable means. The shanks 31 are wrapped at their outer portions, their inner terminals 33 being preferably embedded in the section 22. The jaws are each composed of a continuously curved outer portion 34, spaced inner portions 35, and connecting end portions 36, the space between the inner and outer curved portions being sufficient to permit the opposite portions of the radiator cap 29 to extend through the jaws, which engage the said cap at opposite sides of the center of the same. When the clamp is applied to the radiator cap of an automobile, it extends upwardly therefrom, and the handle or bar extends upwardly and outwardly at an inclination, the bifurcated portions of the sections being beveled to set the handle or member at the desired inclination. The clamp enables the toy to be readily applied to and removed from various types of vehicles.

What is claimed is:—

1. A toy of the class described including a supporting member having a tapered end, a

spindle extending from the tapered end of the supporting member, spaced wind wheels 40 having hubs arranged on the spindle, the hub of the inner wheel fitting against the tapered end of the supporting member, an oppositely tapered sleeve mounted on the spindle and interposed between the hubs of 45 the wind wheels, and an outer tapered or conical sleeve mounted on the spindle and fitting against the hub of the outer wind wheel.

2. A toy of the class described including a 50 supporting member, a wind wheel mounted thereon, and a clamp comprising fixed and movable sections provided with opposite engaging portions, the movable section being 55 slidably interlocked with the supporting member, and the fixed section being secured thereto, and adjusting means connecting the sections.

3. A toy of the class described including a supporting member, a wind wheel mounted 60 thereon, and a clamp comprising fixed and movable sections having engaging portions, the fixed section being secured to the said member, adjusting means connecting the sections, and jaws projecting from the sections and consisting of transversely curved 65 loops arranged to receive and engage the radiator cap of an automobile.

In testimony that I claim the foregoing as my own, I have hereto affixed my signature in the presence of two witnesses.

JACOB POLE.
